UNITED STATES PATENT OFFICE.

**FREDERICK SCHWARTZ, OF BROOKLYN, NEW YORK, ASSIGNOR TO DAVID M. GILBERT,
OF BROOKLYN, NEW YORK.**

DESIGN FOR AN ELECTRIC-LIGHT GLOBE.

48,201.

Specification for Design.

Patented Nov. 23, 1915.

Application filed July 9, 1915. Serial No. 38,997. Term of patent 3½ years.

To all whom it may concern:

Be it known that I, **FREDERICK SCHWARTZ**, a citizen of the United States, and a resident of the borough of Brooklyn, county of Kings, and State of New York, have invented a new, original, and ornamental Design for an Electric-Light Globe, of which the following is a specification, reference being had to the accompanying drawings, forming a part hereof.

Figure 1 is a side elevation of the electric light globe embodying the design. Fig. 2 is a plan view thereof.

I claim:

The ornamental design for an electric light globe, as shown.

FREDERICK SCHWARTZ.

Witnesses:

**HELEN M. DAMES,
IDA G. GILMORE.**
